CLAIM

The ornamental design for a connector housing, as shown and described.

DESCRIPTION

FIG. 1 is a top right perspective view of connector housing showing our new design;

FIG. 2 is a bottom left perspective view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The broken line showing of the various unshaded regions of the connector housing represents unclaimed subject matter and forms no part in the claimed design.
